[57] ABSTRACT

Ice-breaking device for electrical separation devices comprising a support for a mobile contact provided with contact fingers affecting a contact bar, characterised in that the bar comprises, at its periphery, studs provided with means for driving the said studs round the bar when manipulating the device.

FIG.3

CIRCUIT BREAKER WITH AUTOMATIC ICE REMOVAL MEANS ON CONTACT BAR

BACKGROUND OF THE INVENTION

1. Field of the Invention

The invention relates to electrical devices whose contacts are subjected to weather conditions.

2. Description of the Prior Art

In this type of device certain disconnectors or separation devices, such as those comprised by outside equipment of the unpluggable type, may be quoted as examples.

These devices comprise, generally, in co-operation, a fixed contact in the form of a bar and a mobile contact in the form of fingers, suitably insulated from the ground and connected by connection straps to a line or to another device. During very cold periods, when these devices are placed on the outside in contact with the damp air, it happens that their contact surfaces and more particularly the bar become coated with a layer of ice, making the operation of the contacts difficult, more particularly on their closing.

To overcome this, it has been contrived to superimpose over the linear movement of the mobile contact in relation to the bar, a rotation movement about the latter. That arrangement, which has, for its object, the causing of a certain disintegration of the ice which may form on the mobile contact and on the bar, proves, however, to be operative only when the layer of ice covering the bar remains slight.

The invention has for its aim a device intended to break the ice coating which, in the previous hypothetical case was accumulated on the bar, even before the contact fingers of the mobile came to bear against it to ensuring the passing of the current.

SUMMARY OF THE INVENTION

The invention has for its object an ice-breaking device for a separation device of an electrical equipment comprising a support for a mobile contact provided with fingers affecting a contact bar, characterised in that there exist, on the periphery of the bar, studs provided with means for driving the said studs about the bar when manipulating the device.

According to another characteristic, the studs are arranged on the lateral face, facing the mobile contact fingers of a wheel whose bar constitutes the axis.

According to another characteristic, the wheel is driven by a stop fixed to the mobile contact fingers affecting a tooth arranged at the periphery of the wheel.

The characteristics and advantages of the invention will become apparent from the description given herebelow referring to an embodiment given by way of an example and illustrated in the figures.

BRIEF DESCRIPTION OF THE DRAWINGS

FIG. 1 is a diagrammatic top view of a device according to the invention.

FIG. 2 is a sectional view about line 2—2 of FIG. 1 with the wheel 8 in FIG. 1 removed.

FIG. 3 is a top view of the circuit breaker assembly in a closed position immediately after the disintegration of the ice.

DESCRIPTION OF THE PREFERRED EMBODIMENT

In the figures, 1 designates a fixed contact assembly comprising a cylindrical contact bar 2 supported by the arms of a clevis 3 subjected to a holding device 4. Two idle wheels 7 and 8, kept away from the arms of the clevis by spacers 9 and 10 have been installed on the ends of the bar 4.

10 A mobile contact support assembly provided with contact fingers 6 and a stop bar 12 in the open position has been shown by a thick line at 5 and the same elements have been shown in the closed position on the contact bar 2 by dotted lines at 5', 6' and 12'.

The wheels 7 and 8 are ratchet wheels, provided, on the one hand, on their periphery with teeth such as 13 and 14 and, on the other hand, on their lateral face, facing the mobile contact fingers 6 and on the surface of the bar 2, with studs such as 11.

15 The operation of the device is as follows. On the closing movement of the mobile contact support 5, shown by the arrow F, at the end of the travel and before the coming into contact of the fingers 6 with the bar 2, the stop bar 12 meshes with one tooth of each of the wheels 7 and 8, this causing their rotation about the fixed bar 2. The studs 11, fixed on the wheels and sunk in the ice coating 15 which has formed round the bar 2, rotate with the wheels 7 and 8, this causing the disintegration of the ice adhering to the bar. The bar is thus rid of the greater part of the ice and the fingers 6 can come into contact with the bar; their rotating movement about the bar, by means of a known rotating device which is not shown, completes the removal of the ice from the bar.

20 35 On opening, the direction of movement of the mobile contact is the opposite to that of the arrow F. The reverse rotation movement of the contact fingers 6 causes the disintegration of the ice adhering to the bar 2 into particles 16.

40 In the case of FIGS. 1 and 2, the ratchet wheels 7 and 8 are provided with teeth all round the periphery of their circumference. Whatever the original position of the teeth of the wheels 7 and 8 may be on the bar 2 forming a fixed contact, the dimensioning of the teeth of the wheels 7 and 8 is such that the stop bar 12 always meshes with a tooth, on closing.

45 In a variant of embodiment of the invention (not shown), the wheels 7 and 8 may comprise only a single tooth; but in the case, a timing and return device provided, for example, by a spring or a counterweight, hold the tooth, when in the open position, in such a position that, on closing, the stop 12 automatically comes into contact with the single tooth of the wheels 7 and 8.

50 55 It is evident that the invention is in no way limited to the embodiment which has been described and has been given only by way of an example; more particularly, without going beyond the scope of the invention, certain arrangements may be modified or certain means may be replaced by equivalent means.

We claim:

1. In an ice-breaking device for an electrical equipment separation device including, a mobile contact supported for movement and provided with fingers engageable with a fixed contact bar, the improvement comprising studs provided on the periphery of the bar, and means for driving, said studs in rotation about the

bar axis in response to movement of said mobile contact.

2. The ice-breaking device according to claim 1, wherein: the studs are arranged on a lateral face, of a wheel rotatably carried by said bar which constitutes the axis of rotation of said wheel.

3. The ice-breaking device according to claim 1, wherein: the wheel is driven by a stop fixed to the mobile contact support, and at least one tooth is arranged on the periphery of the wheel in the path of movement of said stop.
